United States Patent Office.

REUBEN BRADY, OF NEW YORK, N. Y.

Letters Patent No. 95,190, dated September 28, 1869.

IMPROVEMENT IN MACHINE FOR FASTENING BOTTOMS TO CANS.

The Schedule referred to in these Letters Patent and making part of the same.

To all whom it may concern:

Be it known that I, REUBEN BRADY, of the city, county, and State of New York, have invented a new and improved Machine for Fastening the Bottoms to Polygonal Sheet-Metal Cans; and I do hereby declare that the following is a full, clear, and exact description thereof, which will enable others skilled in the art to make and use the same, reference being had to the accompanying drawings, forming part of this specification, in which—

Figure 1 represents a sectional elevation of my improved clamping-machine.

Figure 2 is a plan or top view of the same.

Figure 3 is a detail enlarged section of the same.

Similar letters of reference indicate corresponding parts.

This invention relates to a new machine for crimping the turned-up edges of sheet-metal plates to the sides of polygonal sheet-metal vessels, so as to thereby securely fasten such plates or bottoms to the vessels.

The invention consists in the general arrangement of a series of slides and of a spring-support, by which the bottom is crimped and supported, as hereinafter more fully described.

A, in the drawing, represents the bed of the machine. In it is provided a four or more sided aperture or depression, for the reception of the can-support.

This is a plate of such size that it will fit into the pan-shaped bottom *a* of the can, as shown.

It is placed upon springs, C C, so that it will be held up about on a level with the slides to receive the can, while it can then be forced down to be lower than the slides, when the machine is in operation.

The slides C C are plates, made of metal, or other suitable material, placed upon the bed A between fixed guide-ribs or plates, *c*, that are secured to or formed on said bed.

The clamping-edges of the slides C are so formed that each one embraces one corner and two half sides of the can, as shown. Each slide is (by a link, *d*, which

is by a pin, *e*, pivoted to the bed A) connected with a ring, E, which ring, when turned, moves the slides in or out, at will.

Each link is, as aforesaid, pivoted to the bed A by a pin, *e*, said pin passing through a slot of the slide, while a pin, *f*, connects the link to the slide.

The bottom, *a*, of the can is, before it is placed upon the machine, stamped, to have a trough-shaped edge, as in fig. 1.

Into this trough is placed the lower edge of the can F, and the can is then forced down by a lever, G.

The ring E is then turned, and the slides are thereby forced against the outer upward-projecting portion *g*, of the bottom, *a*, clamping the said portion and the lower part of the can between the bevelled edges of the plate B and slide C, as shown in fig. 3. The lower part of the can-body, as well as the outer part of the bottom, *a*, is thus forced outward, as shown in fig. 3, so that the bottom is thereby firmly clamped to the can.

For spice-boxes, &c., this invention is of great value. The slides, instead of being on a horizontal bed, may, if desired, be worked on an inclined support.

This invention is equally applicable to cans which have ventilated covers.

Having thus described my invention,

What I claim as new, and desire to secure by Letters Patent, is—

1. The combination of a yielding bevelled can-support, B, with slides C C and actuating-ring E, all arranged and operating as set forth.

2. The arrangement, on the bed A, of the actuating-ring E and the levers *d*, swinging on movable fulcra, and impelling the slotted slides C, in the manner described.

REUBEN BRADY.
